UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPGRAPHICAL MACHINE.

1,129,576.

Specification of Letters Patent. Patented Feb. 23, 1915.

Application filed January 22, 1913. Serial No. 743,474.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 20 form a slug or linotype against the matrices which produce the type characters thereon, and the matrices thereafter returned through a distributing mechanism to the magazine from which they started.

25 More particularly, it relates to machines of this description when provided with a plurality of fonts or sets of matrices, ordinarily stored in a corresponding plurality of magazines, any one of which may be brought 30 into operation at will, the primary object of the invention being an automatic change from one font or set to another, mechanically and in the ordinary course of operation, without requiring the special attention or any manual act of the operator. Obviously, this result may be secured in many 35 different ways and by a variety of mechanical arrangements. For the purposes of illustration, I have shown one font change as effected from a periodically-operated manually-operable part, and another font change as effected from a periodically-operating mechanically-operated part.

In the accompanying drawings, I have 45 illustrated my improvements in preferred form and by way of example, and as applied to the style of machine presented for instance in Letters Patent of the United States to G. A. Bates, No. 719,422; but I am not 50 confined to any such application, as many changes and alterations may be made in the invention, and in its mode of application, and still be comprised within its spirit. In addition, the same principles may be adapted 55 to other forms of typographical ma-

chines, such as type setters, type casters, and the like, which handle type or dies instead of matrices. Generally speaking, I desire it to be understood that I do not limit myself to any specific form or embodiment, except in so far as such limitations are specified in the claims.

60 Referring to the drawings: Figure 1 is a side view of a portion of the machine partly in section and broken away, with my invention applied thereto; Fig. 2 is a detached perspective view of the specific shifting means employed; and Fig. 3 is a diagrammatic view indicating the characters and spacers in a composed line.

65 The matrices are as usual stored in the magazines A and A', which are provided respectively with two series of escapements B and B', the latter being arranged to be actuated by a single series of reeds C. Only 70 two magazines are illustrated herein, but the same principles may be applied to any desired number thereof. The respective escapements B or B' are permitted to operate, at will, or are locked against operation by 75 the rock shafts E and E', the parts being so arranged that when one series is free to be moved, the other is held firmly. In Fig. 1, the upper magazine A is indicated as in operative relation to the throat D and other 80 assembling devices. So far, the parts referred to, and their mode of operation, are or may be substantially like those disclosed in the said Bates patent, and their specific 85 form constitutes in itself no part of my present invention.

90 The spacer escapement (not shown) is of the usual construction, such for instance as that presented in the Bates patent, and is actuated by the lever F. The lever F is operated by the reed G, cam yoke G', cam G², and rotating roll G³, the cam yoke being in turn controlled by the trigger G⁴, slide G⁵ and key H, in such manner that when the key H is touched, the lever F is reciprocated 95 to deliver a spacer, all in the manner well understood in the art.

100 I have preferably selected the spacer-releasing means to effect the change of font and magazine previously mentioned, and to 105 that end I employ an additional reed J, and connect it to an arm J' on the locking rock shaft E. The two rock shafts E and E' are arranged to operate in unison, by the arms J² thereon and the connecting link J³, in 110

such manner that when one is turned to operative position, the other is simultaneously moved to inoperative position. The reed J is actuated from the spacer cam yoke G', the front portion of which is sufficiently broadened to engage both the reeds G and J; so that when the key H is operated in the usual course, not only will a spacer be delivered thereby, but also the rock shafts E and E' will be turned to lock the escapements of the active magazine and to unlock the escapements of the other. This action results in a change of font, as will be understood by those familiar with the art. I have also provided means whereby after the change of font has been thus effected, the key H may be operated for the sole purpose of delivering spacers, the adjusted relations of the magazines being not disturbed thereby, but continuing until another definite point in the cycle of operation. To this end, the reed J is formed with a projecting portion J⁴, adapted to be engaged by the pawl lever K, when the reed is elevated, the pawl lever K being normally pressed inward by the spring K'. As a result of this arrangement, after the key H has been operated, and the reed J elevated to change the operative relations of the magazines, the reed will be held in its uppermost position, until the pawl K is disengaged from the projecting portion J⁴. This disengagement I also accomplish automatically, and in the form shown, preferably by the shifting of the assembled line.

As in the patents previously referred to, when the line is composed, the assembler is elevated to move the line between the fingers M and to trip the transfer slide N, which is then shifted by the transfer lever O toward the first elevator. Connected to the upper end of the pawl lever K is a horizontal slide L, suitably mounted upon the frame work and normally urged toward the lever O by the connected spring L', in such manner as to tend to turn the pawl lever K and release the reed J. This tendency is, however, normally resisted and controlled by the contact of the lever O with the head L² of the slide L. In other words, in the normal position of the lever O, the pawl K is held in operative position to sustain the reed J, and is released therefrom by the periodical movement of the lever. The reed J now descends, the positions of the locking rock-shafts E and E' are reversed, and the return change of font is thereby effected. When the lever O moves again to normal position, it contacts with the head L² and resets the slide L and pawl lever K.

In Fig. 3, I have illustrated diagrammatically one mode of operation of my improved devices, assuming as an example, that it be desired to cast short lines repeatedly and in rapid succession, as is required in connec-

tion with telephone directories or the like, and wherein part of the matter is set in one font, and another part in another font. Thus, it may be desired to compose the name in "black face," and the address, etc. in ordinary characters, as is specifically shown in Fig. 3. Under this arrangement the former matrices would be stored in the magazine A, from which the name would be set up in the ordinary manner. If spacing be required within the name, this may be effected by the insertion of blank spaces or quads. At the end of the name, the key H is operated and a spacer Y delivered, and as a further result of this operation, the magazine A is taken out of action, and the magazine A' rendered operative. The remainder of the line is then set up from the latter magazine, and during such composition additional spacers Y may be freely used, due to the locking of the reed J by the detent K in the manner previously described. The forwarding of the line to the casting devices then releases the reed J, and the magazines are restored to their original relations, when the same steps may be repeated as often as desired. It will be seen that these changes of font are effected entirely automatically, that is to say, by operations regularly and necessarily occurring in the actual use of the machine, whether manual or mechanical, and without requiring either physical effort or special attention from the operator. As previously stated, the invention has been shown only in preferred form and by way of example, and as applied to a specific style of mechanism, wherein the change of magazine and font is secured in one instance by the necessary operation of the spacer key, and in the other instance by the delivery of the composed line. Obviously, however, the change may be made dependent upon other periodically occurring operations and its strictly automatic character be still preserved. Variations and modifications in these respects, as also in the form and arrangement of the parts, will readily suggest themselves to those skilled in the art, without departure from the scope of the invention.

Having thus described my invention, its construction and mode of operation, what I claim and desire to secure by Letters Patent of the United States is, as follows:

1. In a typographical machine, the combination of a plurality of sets of type or matrices, each set comprising a complete font, and means rendered active automatically during the operation of the machine for changing from one set to another.
2. In a typographical machine, the combination of a plurality of separately-usable magazines for the type or matrices, and automatic means for bringing a selected one into use, the said automatic means being

thrown into action by a regularly and automatically operated element of the machine.

3. In a typographical machine, the combination of a plurality of fonts of type or 5 matrices, manually controlled devices for delivering type or matrices of one or another of the several fonts, and means rendered active automatically during the operation of said manual devices for controlling the font 10 of the type or matrices delivered.

4. In a typographical machine, the combination of a plurality of separately-usable 15 magazines for the type or matrices, periodically operated manual means for effecting the actuation of a part of the machine, and connections therefrom for conjointly effecting a change of magazine, together with automatic mechanism for making and breaking said connection alternately.

20 5. In a typographical machine, the combination of a plurality of fonts of type or matrices, an escapement, a key for operating the escapement, and connections from said key to effect also a change of font.

25 6. In a typographical machine, the combination of a plurality of separately-usable magazines for the type or matrices, spacer releasing means, a key for actuating the same, and connections from said key to effect 30 a change of magazine.

35 7. In a typographical machine, the combination of a plurality of fonts of type or matrices, a key, and connections therefrom to release a spacer and also to effect a change of font.

40 8. In a typographical machine, the combination of a plurality of separately-usable magazines for the type or matrices, line transfer devices, and connections therefrom to effect a change of magazine.

45 9. In a typographical machine, the combination of a plurality of fonts of type or matrices, manually operable means to effect a change of font, and mechanism to effect another change of font, the said mechanism being thrown into action automatically by a mechanically operated part of the machine.

50 10. In a typographical machine, the combination of two separately-usable magazines for the type or matrices, manually operable means to effect a change from one magazine to the other, and mechanism to effect the return change of magazine, the said mechanism being controlled automatically by a mechanically operated part of the machine.

55 11. In a typographical machine, the combination of a plurality of separately-usable magazines for the type or matrices, a key,

and connections therefrom to deliver a spacer and also to effect a change of magazine, and connections to the line transfer devices to effect another change of magazine.

60 12. In a typographical machine, the combination of a plurality of separately-usable magazines for the type or matrices, an automatically operated part of the machine, and mechanism rendered active thereby to effect a change of magazine.

65 13. In a typographical machine, the combination of a plurality of separately-usable magazines for the type or matrices, and means for effecting a change from one magazine to another, the said means being rendered active automatically at a predetermined point in the composition of a line.

70 14. In a typographical machine, the combination of a plurality of separately usable magazines for the type or matrices, and means for effecting a change of magazine, the said means being rendered active automatically after the composition of each line.

75 15. In a typographical machine, the combination of a plurality of sets of type or matrices, those of one set being of a different font from those of another set, and means rendered active automatically during the composition of a line for changing from one set to another.

80 16. In a typographical machine, comprising type or matrices of different fonts, the combination of means rendered active automatically during the composition of a line for changing from one font to another, and means rendered active automatically after the composition of said line for returning to the initial font.

85 17. In a typographical machine, the combination of a plurality of fonts of type or matrices, means for delivering a spacer, connections therefrom to effect a change of font, and means to permit the delivery of additional spacers without further change of font.

90 18. In a typographical machine, the combination of a plurality of fonts of type or matrices, means for delivering a spacer, and connections therefrom to effect a change of font, means to permit the delivery of additional spacers without further change of font, and additional means to effect another change of font.

In testimony whereof I affix my signature in presence of two witnesses.

DAVID S. KENNEDY.
